Primary Examiner — Wendy L Arminio(74) *Attorney, Agent, or Firm* — Tucker Ellis LLP(57) **CLAIM**

The ornamental design for a bottle top, as shown and described.

DESCRIPTION

FIG. 1 is a top-front-left perspective view of a bottle top showing my new design;

FIG. 2 is a bottom-front-left perspective view thereof;

FIG. 3 is a top view thereof;

FIG. 4 is a left side view thereof;

FIG. 5 is a right side view thereof;

FIG. 6 is a rear view thereof; and,

FIG. 7 is a front view thereof.

The broken line in FIG. 2 depicts the boundary of the claim that, along with the space contained inside of it, form no part of the claimed design. The remaining broken lines are for the purpose of illustrating portions of the bottle top that form no part of the claimed design.
